CARRY-ALL VANITY CASE

Milton M. Spitalny, Hillside, N. J.

Application March 28, 1950, Serial No. 152,395

2 Claims. (Cl. 132—79)

1. This invention relates to carry-all vanity cases.

The carry-all vanity case which is herein described and claimed may best be described as a duplex case or a combination cigarette and vanity case. It has two compartments, one containing a powder puff and powder holder, and the other containing cigarettes and a lipstick holder. The two compartments are separated from each other by means of at least one wall or partition. Each compartment has its own hinged cover and a torsion spring which normally urges the cover to open position. The cover to the powder and powder puff compartment is also provided with a small mirror which is ready for use when the cover is in open position.

The hinges of the two covers are in alignment with each other and said covers occupy side-by-side positions relative to each other on the top of the case. A slidable locking member is mounted on the case to hold the two covers down in closed position relative to their respective compartments and to release either of the covers for movement to open position in response to the action of the torsion spring thereon. The slidable locking member is a band which encircles the case. It is sufficiently wide to overlap or overlie adjacent portions of the two covers at the same time. It is movable in either direction, that is toward either of the two covers. When it is moved toward the cover of the powder compartment and it clears the cover of the cigarette compartment, the latter cover will swing to open position in response to the action of its torsion spring. When it is closed manually against the action of the spring, it may be locked in closed position by sliding the locking member over upon it. If the locking member is moved a sufficient distance to clear the cover of the powder compartment, said cover will swing to open position in response to the action of its torsion spring. This cover, too, may be closed manually and it may be locked in place by moving the locking member over to engage it. When the locking member partly overlies both covers, they are both locked in closed position.

It is, accordingly, the principal object of this invention to provide a carry-all vanity case of the character described, having the constructional features above set forth. These constructional features make for an extremely handy case which may be carried in the hand in place of a conventional handbag. Nonetheless, it is sufficiently compact to fit into a conventional handbag, should that be desired.

Preferred forms of this invention are shown in the accompanying drawing, in which:

2. Fig. 1 is a perspective view of a carry-all vanity case made in accordance with one form of this invention, the cover to the powder compartment being shown in open position, the cover to the cigarette compartment being shown locked in closed position, and being partly broken away to expose the contents of the cigarette compartment, including the lipstick holder.

Fig. 2 is a fragmentary plan view of the same vanity case, wherein the locking member and the two covers are partly broken away to expose the partition which separates the two compartments.

Fig. 3 is a view similar to that of Fig. 2 showing a modified construction wherein each of the two compartments may constitute a separate container, the two containers being securely fastened to each other in the same relative positions as those occupied by the two compartments in the first form of the invention.

Fig. 4 is an end view of the carry-all vanity case shown in Fig. 3, showing a lipstick holder mounted therein.

Referring now to the first form of this invention and to Figs. 1 and 2, it will be seen that the carry-all vanity case 10, shown therein, comprises a case 11, a partition 12 in said case which divides it into two compartments 13 and 14 respectively, a hinged cover 15 for compartment 13, a hinged cover 16 for compartment 14, and a slidable locking member 17 which locks the two covers in closed position. Compartment 13 is a cigarette compartment and it is adapted to accommodate a plurality of cigarettes 20. Compartment 13 also has a tube 21 for a lipstick holder 22 mounted therein. The lipstick holder is slidably accommodated by said tube 21 and it may be readily slipped into or out of said tube, as and when desired. Tube 21 extends transversely of the case and there is an opening 23 in the wall of the case through which lipstick holder 22 may be pushed into or pulled out of said tube 21. Compartment 14 is the powder compartment of the vanity case, and it is adapted to receive and hold a quantity of face powder as well as a powder puff 24. Affixed to the underside of powder compartment cover 16 is a mirror 25, and it will be seen in Fig. 1 that when said cover 16 is in open position, said mirror 25 occupies a position ready for use.

It will be noted in the drawing that a wire 30 serves as the pintle of the hinges of the two covers 15 and 16. This wire extends lengthwise of the vanity case, and it is carried by the two end walls 31 and 32 of the vanity case, as well as by its partition 12. Torsion springs 33 and 34 are

mounted on said wire 30, adjacent the partition 12, and they engage covers 15 and 16 respectively, to urge them into open position. Fig. 1 shows cover 16 occupying this open position in response to the action thereon of spring 34. The same figure shows cover 15 occupying its closed position against the action of spring 33, by reason of the fact that it is held in such closed position by the locking member 17.

It will be seen that the end walls of the vanity case are elliptical or oval in shape, and it will be understood that the case itself, in transverse cross-section, and with its covers in closed position, is correspondingly elliptical or oval in shape. So, of course, is the locking member 17 which simply comprises an oval band slidably mounted on the oval case. This locking band is slidable in the direction of the arrow in Fig. 1 until it engages a stop member 40. It is also slidable in the opposite direction until it engages a similar stop member 41.

The carry-all vanity case 45 shown in Figs. 3 and 4 is similar to the carry-all vanity case 10 above described, except that it comprises two separate cases 46 and 47, respectively, which are fastened together, instead of a single case 11 which is partitioned off into two compartments. Case 46 provides the cigarette compartment 48 and case 47 provides the powder compartment 49. The cover 50, similar to cover 15, covers cigarette compartment 48 and a cover 51, similar to cover 16, covers powder compartment 49. Torsion springs 52 and 53, respectively, mounted on pintles 54 and 55, respectively, urge covers 50 and 51 to open position. Slidable locking band 56 locks said covers in closed position.

It will be noted that the adjacent end walls 57 and 58 of the two cases 46 and 47 abut each other and serve as the partitions between the two compartments 48 and 49. These two walls 57 and 58 may be fastened to each other by any conventional means, as for example by means of rivets, spot welding or the like. Cases 46 and 47 are also provided with stop members 60 and 61, respectively, corresponding to the two stop members of the first form of this invention, to limit the movement of the slidable locking band 56. A lipstick holder 22 may be used in this modification in the same manner as in Fig. 1. However, if desired, a lipstick holder 63 having a hinged pull-tab 64 may be mounted endwise in case 46. A tube corresponding to tube 21 may be mounted in said case 46 and a circular hole 65 is then provided in end wall 66 of said case 46 to provide ingress and egress for the lipstick holder 63.

It will be understood from the foregoing that the vanity case shown in the drawing may be modified in many ways, and other forms of the invention may be provided all within the broad scope and spirit of the invention.

Having thus described my invention, what I claim as new and desire to secure by Letters Patent, is:

1. A carry-all vanity case of the character described, comprising an elongated case, a partition in said case to divide the case into a face

powder receiving compartment on one side of the partition and a cigarette receiving compartment on the other side of the partition, a first spring-urged hinge mounted on said case adjacent the powder compartment and disposed on a line parallel to the longitudinal medial line of said elongated case, a second spring-urged hinge mounted on said case adjacent the cigarette compartment and parallel to said first hinge, a cover for the powder compartment mounted on the first mentioned hinge, a cover for the cigarette compartment mounted on the second mentioned hinge, said covers being normally urged into open position relative to said compartments by their respective spring-urged hinges, and a locking member which holds such covers in closed position relative to said compartments against the action of their said spring-urged hinges, said locking member comprising a band which is slidably mounted on the case for movement into overlying position relative to said covers in order to hold them captive in closed position, said band being very narrow relative to the longest dimension of the elongated case whereby only a very minor portion of the case is covered by said band which thus presents an ornamental appearance.

2. A carry-all vanity case of the character described, comprising an elongated case which is oval-shaped in cross section, a partition in said case which divides the case into a face powder compartment on one side of the partition and a cigarette compartment on the other side of the partition, a spring-urged hinge mounted on the case adjacent the powder compartment, a second spring-urged hinge mounted on said case adjacent the cigarette compartment, said hinges being in substantial end-to-end alignment with each other, a cover for the powder compartment mounted on the first mentioned hinge and having a mirror mounted on the inside thereof, a cover for the cigarette compartment mounted on the second mentioned hinge, said covers being normally urged into open position relative to said compartments by their respective spring-urged hinges and an oval-shaped locking band which is slidably mounted on the case for movement into overlying position relative to said covers to hold them captive in closed position, said locking band being movable out of engagement with either of said covers to release the same for movement into open position, said band being very narrow relative to the longest dimension of said elongated case and covering only a minor portion thereof.
